Primary Examiner—Robin V. Webster*Assistant Examiner*—Karen E Kearney(74) *Attorney, Agent, or Firm*—The Soni Law Firm(57) **CLAIM**

The ornamental design for a flash drive radio, as shown and described.

DESCRIPTION

FIG. 1 is a front side bottom perspective view of my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a back elevational view thereof.

The broken lines showing of the numbers within the display in FIGS. 1 and 2 are for the purpose of illustrating unclaimed portions and form no part of the claimed design.
